UNITED STATES PATENT OFFICE.

CHARLES A. BACKSTROM, OF MILWAUKEE, WISCONSIN, ASSIGNOR TO BACKSTROM-SMITH STEAM TURBINE & MANUFACTURING COMPANY, A CORPORATION OF WISCONSIN.

TURBINE RUNNING-WHEEL.

No. 856,207.

Specification of Letters Patent.

Entered June 11, 1907.

Application filed October 8, 1904. Renewed April 22, 1907. Serial No. 369,574.

To all whom it may concern:

Be it known that I, CHARLES A. BACKSTROM, a citizen of the United States, residing at Milwaukee, county of Milwaukee, and State of Wisconsin, have invented new and useful Improvements in Turbine Running-Wheels, of which the following is a specification.

My invention relates to improvements in turbine running wheels.

The object of my invention is to provide a form of construction in which the vanes are held in position by mutual support and the co-operative action of the wheel rims interlocking with the vanes, thus relieving the strain upon the bolts or rivets and facilitating the assemblage of the various parts.

A further object of the invention is to provide a form of construction in which each vane co-operates with the one preceding it in providing a bucket cavity of gradually increasing capacity from the point where it receives the motive fluid to the point of fluid discharge.

In the following description, reference is had to the accompanying drawings in which my invention is shown applied to a running wheel designed for an inward delivery of motive fluid.

Figure 1 is a detail side view of a rim portion of a turbine running wheel embodying the invention and with one side disk partially broken away to show the vanes. Fig. 2 is a detail peripheral view with the thicker side disk partially broken away to show the vane receiving channel. Fig. 3 is a radial sectional view of a rim portion of the wheel showing one of the vanes from the concave face. Fig. 4 is a sectional view of one of the vanes drawn on line $x-x$ of Fig. 5. Fig. 5 is a detail view in radial section showing one of the vanes from the convex face.

Like parts are identified by the same reference characters throughout the several views.

1 and 2 are the rim walls, preferably comprising the outer portions of a pair of disks composing the side walls of the wheel and between which the vanes 3 are mounted. The wall 2 is preferably thicker than the wall 1

and is recessed annularly, preferably being provided with an annular channel 4 into which a portion a of the end wall b of the vane extends and fits the channel. The end wall b of the vane projects from its convex face 55 and fits the concave face of the succeeding vane, all the vanes being thus arranged to abut each other in the channel 4 and adjacent thereto. The wall b is also formed with an inclined inner surface C so that in thickness it tapers from the point of motive fluid reception to the point of fluid discharge, thus increasing the dimensions of the bucket space in the direction of flow.

Rivets 6 are used to hold the rim walls 1 65 and 2 together. These are preferably passed through holes 7 between the concave and convex walls of the vane, the holes being made sufficiently large to permit the insertion of the rivets, without requiring machine work 7c to correct such slight inaccuracies as may exist. The principal function of the rivets, however, is to bind the rim walls together, the latter being relied upon to hold the vanes in position.

Having thus described my invention what I claim as new and desire to secure by Letters Patent is.

1. In a turbine running wheel, a set of rim walls, one of which is provided with a recessed inner face; a series of vanes, each having an end wall, notched in its outer portion and formed to project into the recessed portion of the rim and fitting the recess; and means for binding the rim walls together; 80 said end wall of the vane having its inner surface inclined from the fluid receiving side toward the side of fluid discharge and the adjacent rim wall.

2. In a turbine running wheel; a set of rim walls; an annular series of vanes located between said walls and arranged to interlock with the rim walls; and means for binding said walls together comprising rivets extending through longitudinal apertures in the 85 vanes.

3. In a turbine running wheel; a set of rim walls; an annular series of vanes located between said walls and arranged to interlock with the rim walls; and means for binding 90

said walls together comprising rivets extending through longitudinal apertures in the vanes of greater diameter than the rivets.

4. In a turbine running wheel, a set of rim walls and a series of vanes secured between said walls; each of said vanes having a projection at one end fitting the next succeeding vane, and each such projection being tapered

from the fluid receiving side of the vane to the side of fluid discharge.

In testimony whereof I affix my signature in the presence of two witnesses.

CHARLES A. BACKSTROM.
